UNITED STATES PATENT OFFICE.

CHARLES HENRY PARKER, OF CODSALL, ENGLAND.

DISTILLATION OF COAL AND SIMILAR CARBONACEOUS SUBSTANCES.

Application filed January 27, 1928, Serial No 249,967, and in Great Britain September 25, 1928.

This invention relates to apparatus for the distillation of coal and similar solid carbonaceous substances and especially for carrying out distillation at low or medium 5 temperatures for the production of a residue that is substantially smokeless in burning in an open grate and that has a substantial volatile content, and especially relates to apparatus of the kind in which the 10 carbonaceous substance is charged into receptacles of cylindrical or elongated form adapted to traverse an inclined retort by rolling through the retort under the action of gravity.

15 The invention has for its object to provide means whereby the carbonaceous substance may be dried before distillation in an economical manner.

According to the invention the charged 20 receptacles, prior to their introduction into the retort, are caused to traverse a chamber or chambers through which the heated waste gases from the heating chambers or flues of the retort setting pass to the chimney or 25 other outlet, so that the carbonaceous substance contained in the receptacles is subjected to the heat of the waste gases and is thus dried.

The chamber or chambers in which the 30 treatment is carried out may be constructed in any suitable manner and may be disposed in any desired position with reference to the retort or retorts to which the receptacles which pass through the chamber or chambers 35 are transferred. Thus, the retort setting may be provided of increased height for the formation of a drying chamber in position above the retort or retorts and the said chamber may be provided with an inclined track, 40 the upper end of which is adapted to receive the charged receptacles from the charging apparatus and the lower end of which is connected to the upper end of the track in the retort by suitable transferring or feed apparatus, or the floor of the chamber may 45 be inclined and suitably formed or fitted with surfaces upon which the receptacles may roll. The receptacles may, moreover, be subjected directly to the heat of the waste 50 gases, which may be caused to pass through the heating chamber in contact with them, or they may traverse an inclined tubular structure disposed within the heating chamber, the waste gases traversing the annular 55 space within the heating chamber around the said tubular structure. The heating chamber

ber may, further, be provided as a connecting flue between the retort setting and the chimney or other outlet by which the waste gases are discharged. 60

It will thus be understood that the invention is not limited to any particular construction of the heating chamber nor to any particular disposition with reference to the retort setting or the retort or retorts with 65 which it is required to co-operate as these may be varied without departing from the invention and without affecting the desired result, which is the shortening of the time required for effecting distillation in the retort or retorts and for reducing the content 70 of moisture present in the ammoniacal liquor.

It will also be understood that while it is desirable that the heating chambers should be of gas-tight construction, this is not essential. 75

The invention is illustrated by way of example in the accompanying drawing which is a partial longitudinal section of the retort furnace setting and of a preliminary 80 heating chamber through which the hot waste gases from the retort furnace passes for the purpose of subjecting the receptacles to the heat of the waste gases for the purpose of drying the carbonaceous substance 85 prior to its entry into the retort.

In the drawing the invention is illustrated as applied to the apparatus for the distillation of carbonaceous substances the subject-matter of a co-pending application. 90

In the drawing *a* are the retorts, *b* the retort furnace and *c* the preliminary heating chamber through which the hot waste gases pass and *d* the receptacles in which the carbonaceous substance is charged and in which it passes through the preliminary heating chamber and through the retort. 95

I claim:

Apparatus for the distillation of coal and similar carbonaceous material, comprising 100 an inclined tubular retort, a tubular preheating casing of considerably greater cross section than said retort and arranged above said retort with its lower end connected to the upper end of the retort, said preheating casing and said retort being arranged to define a continuous descending passageway of zig-zag formation, a setting in which said retort and said preheating casings are supported and having passages therein about 105 said retort but not about said preheating casing for the distribution of heating gases, 110

substantially cylindrical receptacles in which the carbonaceous material is charged adapted to roll in and be guided by said pre-heating casing and said retort, said receptacles having perforated ends, and means for sealing the upper end of said preheating casing and the lower end of said retort, said

receptacles being of such dimension as to substantially fill said retort, whereby said receptacles are subjected to the heating action 10 of a large quantity of accumulated products of distillation during their passage through said preheating casing.

CHARLES HENRY PARKER.
